(57) **CLAIM**

The ornamental design for a welding torch, as shown and described.

DESCRIPTION

FIG. 1 is a bottom perspective view of a welding torch showing our design;

FIG. 2 is a top perspective view of the welding torch of FIG. 1;

FIG. 3 is a bottom plan view of the welding torch of FIG. 1; FIG. 4 is a top plan view of the welding torch of FIG. 1; FIG. 5 is a left side elevational view of the welding torch of FIG. 1;

FIG. 6 is a right side elevational view of the welding torch of FIG. 1;

FIG. 7 is a front elevational view of the welding torch of FIG. 1; and,

FIG. 8 is a rear elevational view of the welding torch of FIG. 1.
